UNITED STATES PATENT OFFICE.

WRIGHT D. BRESEE, OF LOS ANGELES, CALIFORNIA.

KEYHOLE GUARD.

Application filed October 1, 1921, Serial No. 504,580. Renewed July 5, 1923.

To all whom it may concern:

Be it known that I, WRIGHT D. BRESEE, a citizen of the United States, residing at Los Angeles, in the county of Los Angeles and State of California, have invented new and useful Improvements in Keyhole Guards, of which the following is a specification.

My invention relates to a device for closing 10 a key hole against the insertion of a key or other article.

An object of my invention is to provide a guard for key holes adapted to be introduced into a key hole and engaged with 15 the walls thereof in such manner as to inhibit insertion of a key or other device and thereby effectively prevent tampering with the lock.

Another object is to provide a device of 20 the above character which is adapted to be locked in engagement with the key hole walls by a key controlled mechanism in such fashion as to effectively hold it in place against unauthorized removal.

A further object is to provide a key hole 25 guard of the above type which is adapted to be employed in key holes of various sizes.

Other objects will appear hereinafter.

The invention is illustrated in the accompanying drawings, in which:

Figure 1 is a view of a lock as seen in transverse vertical section through the key hole, showing the manner of applying the guard and illustrating it in its open and 30 locked position.

Figure 2 is a view of the guard as seen in side elevation, showing it in its closed position.

Figure 3 is a view of the guard as seen in 40 longitudinal vertical section with parts in elevation.

Figure 4 is a rear end view.

Figure 5 is a front end view.

Figure 6 is a view in section as seen on the 45 line 6—6 of Figure 3.

In carrying out my invention, I employ a tubular casing 7 preferably formed of cast metal and having its interior provided with two concentric cylindrical chambers of different diameters; the smaller chamber 8 opening at the outer end of the casing and the larger chamber 9 opening at the inner end thereof. The bottom wall of the casing is formed throughout with a longitudinal slot or channel 10 which opens to the chamber 9 and mounted in this channel is a sheet 50

metal housing 11 comprising parallel side walls *a*—*b*, a bottom wall *c* and an end wall *d*; the housing being inserted in the channel and brazed to the casing with the end wall 60 *d* extending adjacent the outer end of the casing and its open end projecting a short distance forward of the inner end of the casing. The open upper end of the housing communicates with the interior of the 65 chamber 9.

A locking arm 12 of flat thin sheet form is pivotally mounted in the housing by a pin 13 and projects through the open end of the housing, and mounted in the housing is a 70 spring 14 adapted to normally retain the arm in an uppermost position. The outer end portion of the arm is formed on its lower edge with a series of serrations or teeth 15.

Revolvably mounted in the chamber 8 is a tubular cylinder 16 formed with a longitudinal slot 17; the outer end of the cylinder being fitted with an end wall 18 having an irregular key slot 19 formed therein to receive a key 20 by means of which the cylinder may be rotated. The outer end of the cylinder seats on an inturned flange 21 formed at the outer end of the casing. Mounted on the inner end of the cylinder 16 80 is an eccentric disk 22 arranged within the chamber 9, which disk constitutes a cam adapted on rotation of the cylinder to act on the arm 12 and against which the arm bears under pressure of the spring 14. 85

The inner end of the casing is closed by a plate 23 which seats against the end face of the disk 22 and is held in place by an in-turned flange or bead 24 on the end of the casing; the plate being formed with a slot 90 25 with which the side walls of the housing are engaged to hold the plate against turning. Rigidly mounted on the end plate and projecting therefrom in axial alignment with the casing is a cylindrical stem 26 of a diameter slightly less than the circular portion of an ordinary key hole. The upper face of the stem is formed with a series of shallow serrations 27 adapted to be engaged with the upper edges of the key hole openings in the 100 plates within a lock.

In the operation of the invention the cylinder 16 is positioned to dispose the cam disk 22 with its overhanging portion clear of the locking arm, so that the latter will be retracted by the spring and held close to the stem substantially in alignment therewith, as 110

shown in Figures 3 and 4. The stem and arm are then inserted in a key hole with the stem arranged in the upper circular portion of the hole and the arm arranged within the 5 depending slot portion of the hole. The cylinder 16 is then turned by the key 20 to cause the cam disk to turn and move the arm 12 downwardly on its pivot and bring the teeth 15 into engagement with the lower edges of 10 the key hole in the plates within the lock and at the same time cause the stem to bear upwardly into engagement with the upper edges of the key hole openings, as shown in Figure 1. The cam disk will then serve to 15 maintain the arm in an open position within the key hole and the serrations of the arm and the stem will hold the device against being disengaged from the lock until the cam and arm are again retracted. When the device is thus secured in place in the key hole 20 the latter will be effectively blocked against the insertion of a key or other implement, so that the lock will be protected against picking or tampering.

25 It will now be seen that I have provided a simple device for carrying out the objects set forth, but while I have described the invention specifically I do not desire to limit myself to the exact details of construction 30 shown, but may employ such changes in the construction and modification of the parts as occasion may require coming within the scope of the invention as set forth in the accompanying claims.

35 I claim:

1. A key hole guard comprising a casing, a

fixed stem on said casing adapted to be inserted in the upper portion of a key hole, a housing on said casing, an arm pivoted in 40 said housing extending beneath said stem in alignment therewith and adapted to be inserted in the lower portion of a key hole, a spring normally maintaining said arm in a retracted position, a cylinder rotatable in 45 said casing having a key receiving slot, and a cam affixed on said cylinder to turn therewith arranged to bear on said arm and adapted on rotation of said cylinder to depress 50 said arm in opposition to said spring and position the arm in spread relation to said stem.

2. A key hole guard comprising a casing, a fixed stem on said casing adapted to be inserted in the upper portion of a key hole, a housing on said casing, an arm pivoted in 55 said housing extending beneath said stem in alignment therewith and adapted to be inserted in the lower portion of a key hole, a spring normally maintaining said arm in a retracted position, a cylinder rotatable in 60 said casing having a key receiving slot, and a cam affixed on said cylinder to turn therewith arranged to bear on said arm and adapted on rotation of said cylinder to depress 65 said arm in opposition to said spring and position the arm in spread relation to said stem; said stem and arm being formed with serrations adapted to be engaged with the upper and lower margins of key hole openings within a lock.

WRIGHT D. BRESEE.
